UNITED STATES PATENT OFFICE.

FREDERICK W. BROWN, OF BOSTON, MASSACHUSETTS, ASSIGNOR TO
THOMAS STANLEY PATERSON, OF SAME PLACE.

DESIGN FOR A BICYCLE-LOCK.

SPECIFICATION forming part of Design No. 28,661, dated May 17, 1898.

Application filed December 18, 1897. Serial No. 862,489. Term of patent 7 years.

To all whom it may concern:

Be it known that I, FREDERICK W. BROWN, a citizen of the United States, residing at Boston, in the county of Suffolk and State of Massachusetts, have invented a new and original Design for a Bicycle-Lock, of which the following is a specification.

The base of the lock is elliptical in plan view, with rounded ends and curved surfaces. From this base rise the locking-horns, which continue unbroken the outline of the base. The horns are symmetrically disposed with reference to either the long or short axis of the base and converge toward the middle above the short axis of the base. The horns follow an ogee curve—in other words, are gooseneck-shaped—and terminate in spreading or flattened heads. The opening between the horns is oval in side view.

In the drawing hereto annexed, which shows the bicycle-lock in perspective, B is the

elongated or elliptical base of the lock, H H the horns, and H' H' the flattened heads of the horns.

C is a projection concaved at the top to 25 form on oval opening with the inner sides of the horns.

The outlines are all continuous and easy and the lock as a whole perfectly symmetrical from whatever point it is viewed.

What I claim, and desire to secure by Letters Patent, is as follows:

The design for a bicycle-lock, substantially as shown and described.

In testimony whereof I have signed my 35 name to this specification in the presence of two subscribing witnesses.

FREDERICK W. BROWN.
